John W. Glenn,
C. A. Snow & Co.

Inventor

UNITED STATES PATENT OFFICE.

JOHN WILLIAM GLENN, OF GRAPE VINE, TEXAS.

WIRE-TIGHTENER.

SPECIFICATION forming part of Letters Patent No. 531,630, dated January 1, 1895.

Application filed July 27, 1894. Serial No. 518,772. (No model.)

To all whom it may concern:

Be it known that I, JOHN WILLIAM GLENN, a citizen of the United States, residing at Grape Vine, in the county of Tarrant and 5 State of Texas, have invented a new and useful Wire-Tightener, of which the following is a specification.

This invention is related to that class of wire-stretching devices which are adapted to 10 stretch the wire after it has been secured to the posts, and to take up any slack which may exist therein, owing to causes arising subsequent to the first stretching of the wires. These devices usually consist of a handle or 15 lever provided with means for connection with the wires, whereby the lever may be operated to tighten the same. Now my invention does not depart from this broad principle, but consists in certain peculiar features 20 of construction whereby the simplicity and efficiency of the device are increased. These differences will be fully described hereinafter, and finally embodied in the claim.

In the drawings: Figure 1 represents a perspective view of the invention, it being shown 25 as practically employed; Fig. 2, a longitudinal section of the same; Fig. 3, a detail perspective of the wire-engaging hooks and the bolt for connecting the same to the lever.

30 The reference numeral 1 indicates the lever, which is formed, by preference, of hard wood, such as oak or walnut, and which is shaped with a reduced and rounded main portion *a*, terminating at its inner end in the enlarged 35 or head-like portion *b*. This part, *b*, is formed rectangular in cross-section and has its outer end rounded, as may be readily seen by reference to the drawings.

2 indicates a facing-plate, which is formed 40 of a strip of plate metal and extended around the edges of the enlarged portion *b* of the lever 1, so as to protect said edges and the rounded point or end aforesaid. This part, 45 2, is held in place by means of the nails or screws 3, which pass through it and into the lever 1, as will be well understood.

Formed in the enlarged portion *b* of the lever 1, and extending transversely therein, are the passages 4, which are preferably five in 50 number and which are arranged equidistant

throughout the length of such portion. These passages are provided for the reception of the bolt 5, which is a spindle in function, and which is provided with the usual head and nut by which it may be secured in place. 55 This bolt is adjustable throughout the length of the enlarged portion *b*, by means of the passages 4, as will be understood.

6 indicates two hooks which are formed of metallic rods, bent to form the eyes *c*, and the 60 hooks proper *d*, the former being at one end and adapted to receive the respective ends of the bolt 5, while the hooks proper are at the free ends, and are provided to engage with the wires of the fence, as shown by Fig. 1. 65 The relative length of the hooks 6 is about equal to that of the enlarged portion *b* of the lever 1; and the adjustment of the said hooks is made possible in order that the varying thicknesses of fence-posts may be compensated for, all of which will be understood. 70

The use of the invention will be well understood, from Fig. 1, and no extended description thereof will be necessary. The device is principally used for tightening the wires and 75 for temporarily holding them until they may be secured at their new tension. To this end the rounded end of the enlarged portion *b* is made to abut against that side of the post which is opposite the side to which the wire 80 is affixed, and the hooks 6 made to extend one on each side of the post, so that the parts *d* thereof will be in position to engage with the wire by hooking over them, as shown in Fig. 1.

It will be understood that it is necessary to 85 adjust the bolt 5 previously, so that the lever 1 will extend, not horizontally, but diagonally either upwardly or downwardly, so that in moving the lever to a horizontal position the hooks 6 will be drawn outwardly and toward 90 the side of the post with which the rounded end of the lever engages. This will draw the wire around the sides of the post and thereby take up the slack thereof. In this position the wire may be held until the new staples 95 are applied, or until the wire is secured by other means, none of which enter into this invention.

Having described the invention, I claim—
A wire tightener consisting of a lever hav- 100

ing at one end an enlarged portion shaped rectangular in cross-section and provided with a rounded outer terminal, a facing-plate formed of a metallic strip and secured to two sides of the said enlarged portion and covering the rounded terminal thereof, the said enlarged portion being formed with a series of transverse passages, a bolt passed through

one of said passages, and two hooks provided with eyes by which they are pivoted on opposite ends of the bolt, substantially as described.

JOHN WILLIAM GLENN.
